UNITED STATES PATENT OFFICE.

GEORGE B. ASHWORTH, OF AMSTERDAM, NEW YORK.

LOCOMOTIVE GRATE SHAKER.

Application filed February 6, 1923. Serial No. 617,285.

To all whom it may concern:

Be it known that I, GEORGE B. ASHWORTH, of Amsterdam, in the county of Montgomery and State of New York, have invented 5 a certain new and useful Improvement in Locomotive Grate Shakers, of which improvement the following is a specification.

The object of my invention is to provide an appliance of simple, compact, and inexpensive construction, which will be adapted 10 to support a plurality of grate shaking levers, in proper position relatively to a locomotive firebox, prevent the dropping of fuel adjacent thereto from the firing deck or 15 platform, and embody suitable means for locking the levers in position.

The improvement claimed is hereinafter fully set forth:

In the accompanying drawing: Figure 1 20 is a side view, in elevation, of a grate shaking appliance embodying my invention, attached in operative position to the back head of a locomotive boiler firebox; Fig. 2, a rear view, in elevation; Fig. 3, a plan view, 25 partly in section; Fig. 4, a vertical transverse section, on the axial line of the fulcrum pin; and, Figs. 5, 6 and 7, detail views of one of the locking members.

In the practice of my invention, referring 30 descriptively to the specific embodiment thereof which is herein exemplified, I provide a support, 1, which is in the form of an open-bottomed casing, preferably as shown, an integral casting, the top portion of which 35 is rearwardly and downwardly inclined, and on which are formed a top flange, 1^a, and side flanges, 1^b, through which it is secured, by bolts, 2, to the back head, A, of a locomotive firebox. When so secured, the support 40 covers an opening in the firing deck or floor, C, of the locomotive, in which it is fitted, and through which the grate shaking levers, presently to be described, extend downwardly to connections with the grate 45 bars of the firebox. A plurality of parallel slots, 1^d, is formed in the top portion of the support, and lugs, 1^e, are also cast upon it. Bottom flanges, 1^f, on the sides and back of the support, extend below and around the 50 opening in the firing deck in which it is fitted, and vertical ribs, 1^g, are interposed between the slots, 1^d.

A transversely extending fulcrum pin, 3, is fitted in the side portions of the support,

and a plurality of grate shaking levers, 4, 55 extend through the slots, 1^d, of the support, and are journalled to be oscillated, independently one of another, on the fulcrum pin. The lower arms of the grate shaking levers are coupled, by links or connecting rods, 5, to separate sets of the grate bars (not shown) in the ordinary manner, and the shaking levers are rocked, as from time to time required, by shaking bars, adapted 60 to be engaged with their upper ends.

The grate shaking levers, 4, are held in their normal stationary positions, when not desired to be operated, by locking members, 7, pivoted to the lugs, 1^e, of the support, 1, each of said members having a central recess, 7^a, adapted to engage one of the shaking levers, and lateral extensions, 7^b, which cover, and completely close, the spaces between the front and rear sides of said lever and the ends of the slot, 1^d, of the support, 75 through which it passes. The locking members thereby present, with the top portion of the support, 1, a practically unbroken surface, down which any fuel that may be dropped in firing, will fall to the firing deck, 80 and not drop through it.

The operation of any of the shaking levers that may be desired, is effected by swinging the locking member thereof upon its pivot in the support and thereby disengaging the 85 lever, which may then be rocked, either manually or by the application of power, in the ordinary manner. When the operation is completed, the shaking lever is returned to its normal middle position, shown 90 in the drawing, and its locking member is swung down on its pivot and engaged with it.

I am aware that locking members, pivotally connected to a support, and adapted to engage shaking levers, are disclosed in Letters Patent prior to my invention, and such appliances, broadly, I therefore disclaim.

I claim as my invention and desire to secure by Letters Patent:

1. In a grate shaking appliance, the combination of a supporting casing, having a plurality of slots in its top portion; a fulcrum pin, fitted transversely in said casing; grate levers, each journalled on said pin, and extending through a casing slot; and locking members, each pivoted to the casing and adapted to engage a grate shaking lever and

cover the spaces between the front and rear sides of said lever and the ends of the slot through which it passes.

2. In a grate shaking appliance, the combination of a supporting casing, having a plurality of slots in its top portion; a fulcrum pin, fitted transversely in said casing; grate levers, each journalled on said pin, and extending through a casing slot; and locking members, each pivoted to the casing and having a central recess adapted to engage a grate shaking lever and lateral extensions, substantially covering the spaces

between the front and rear sides of said lever and the ends of the slot through which it passes. 15

3. In a grate shaking appliance, a locking member for a grate shaking lever, having a central recess for engagement with said lever, lateral extensions adapted to cover a slot in which said lever is to swing, and eyes for the reception of a pivot pin. 20

GEO. B. ASHWORTH.
